ATTY'S.

UNITED STATES PATENT OFFICE.

GEORGE GIBBS, OF NEW YORK, N. Y.

CAR CONSTRUCTION.

No. 806,468.

Specification of Letters Patent.

Patented Dec. 5, 1905.

Application filed May 3, 1905. Serial No. 258,611.

To all whom it may concern:

Be it known that I, GEORGE GIBBS, a citizen of the United States, residing at New York, State of New York, have invented a certain new and useful Improvement in Car Construction, of which the following is a full, clear, and exact description, such as will enable others skilled in the art to which it appertains to make and use the same, reference being had to the accompanying drawings, forming part of this specification, in which—

Figure 1 is a fragmentary vertical sectional view through a portion of a car-roof constructed in accordance with my invention. Fig. 2 is a fragmentary side elevational view of the same, and Fig. 3 is a slightly-modified form.

This invention relates to railway-cars, and particularly to steel passenger-cars.

One of the objects of the invention is to provide means for efficiently fastening a car-roof to the car-body, so that any liability of moisture being introduced into the joints will be avoided.

Other objects and advantages, as well as the novel details of construction of this invention, will be specifically described hereinafter, it being understood that changes in form, proportion, and minor details of construction may be resorted to without departing from the spirit of my invention or sacrificing any of the advantages thereof.

Referring now to the drawings, and particularly Fig. 1, showing the preferred form of my invention, 1 designates the side plate, illustrated as comprising an angle having a vertical flange and an inwardly-projecting horizontal flange.

2 designates a metallic eaves-molding, illustrated as comprising a horizontal flange secured to the top of the side plate 1 by rivets 3 and having an outwardly and downwardly deflected flange with an inwardly-disposed projecting edge intermediate its ends, which bears against the vertical flange of the side plate and which bears intermediate its ends against the upper edge of the facia-plate 4, riveted to the side plate and extending beneath the downwardly-deflected flange of the molding, so that a tight joint is made at 5 by spring-pressure. Of course it is to be understood that any type of fastening device may be utilized for securing the molding to the side plates. In order to provide a water-tight joint between the juncture of the roof-

covering 6, which rests upon the horizontal flange of the molding, and the metallic molding; I provide a flasher 7, of sheet metal, which extends beyond the joint made by the juncture of the roof-covering and the molding, 60 the lower edge of said flasher being adapted to be soldered to the deflected flange of the molding. After the parts are thus assembled I apply a canvas covering 7^a over the roof, the lower edge of which overlaps the upper 65 edge of the flasher, and the flasher and canvas covering are then secured in place by suitable fastening devices, such as nails 8. The roof is braced on each side of the car by a filler 9, which rests upon the horizontal flange of the 70 side-plate angle and bears against the roof-covering 6, said filler being secured in place by means of bolts 10.

In the construction illustrated in Fig. 3 the molding is eliminated, and the roof-covering 75 6 is illustrated as resting upon the horizontal flange of the side-plate angle, and the facia-plate 4 extends up to a point flush with said horizontal flange. The outer edge of the covering 6 is flush with the outer face of the 80 facia-plate, and the flasher-sheet 7 is secured to the covering and facia-plate, so as to overlap the joint made by the juncture of the facia-plate and the roof-covering, and the canvas covering 7^a is then applied to the roof-covering 6, so that its lower edge will overlap the flasher, to which it may be secured by fastening devices, (illustrated as the nails 8,) which pass through the canvas covering, the flasher, and the roof-covering 6. The lower 90 edge of the flasher is secured to the facia-plate by any suitable means—as, for example, by the fastening devices 11.

It will be seen from the foregoing that the roof arrangement is such that the introduction of moisture between the joints will be efficiently prevented.

Having thus described the invention, what is claimed as new, and desired to be secured by Letters Patent, is—

1. The combination with the sides of the car, of a roof supported above the upper edges thereof, a molding-strip having a portion extending outwardly from said sides, and a portion interposed between the roof and the upper edges of said sides, facia-plates carried by the upper portions of said sides and against which the outwardly-projecting portion of the molding rests, a flasher-strip carried by the roof-covering and overlapping the molding, 105 110

and a covering carried by the roof-covering and overlapping the flasher-strip; substantially as described.

2. In a railway passenger-car, the combination with metallic sides having inwardly-disposed horizontal flanges, molding-strips carried by said flanges and having outwardly and downwardly deflected portions, a roof-covering supported above the sides of the car, a 5 flasher-strip carried by said roof-covering and overlapping the molding, and a covering carried by said roof-covering and overlapping the flasher-strip; substantially as described.

3. The combination with the sides of a car, a 10 roof supported above the upper edges 15 of a roof supported above the upper edges

thereof, a molding-strip having a portion extending outwardly from said sides, facia-plates carried by the upper portions of said sides, and a flasher-strip carried by the roof-covering overlapping the molding, and a covering carried by the roof-covering and overlapping the flasher-strip; substantially as described. 20

In testimony whereof I hereunto affix my signature, in the presence of two witnesses, this 27th day of April, 1905.

GEORGE GIBBS.
